AUTOMATICALLY RELEASED FUSE LINK
STICK

Helmer C. Halvorson, Lennox, S. Dak.

Application March 18, 1949, Serial No. 82,135

3 Claims. (Cl. 294—19)

1

This invention relates to implements and sticks for installing fuses and fuse links upon fuse switches, connections to electrical devices, and circuits in elevated positions, as for example upon poles, and refers to an automatically-released fuse link stick which I prefer to term the 96 fuse stick.

The main object of my invention is to provide a manually-held means for applying fuse links and which automatically releases the fuse involved when installed.

Another object is to provide a fuse link stick for elevating a fuse of a special type termed a fuse link into position on a high switch structure or pole without danger of the fuse becoming accidentally displaced from the stick while being raised into position and dropping to the floor or ground, making it necessary for the lineman to climb down from the ladder or pole to place a new fuse link on the stick.

A further object is to provide a fuse stick of the character indicated with means which serves not only to retain the fuse in place during raising and installation of the fuse, but which automatically releases the latter when installed merely by lowering the fuse stick from the operating position.

It is also an object to have such a fuse stick which is simple in form, easy and convenient to use and effective in operation.

Other objects and advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a side elevation of an automatically-released fuse link stick made according to the invention and embodying the same in a practical form, the device being shown in operative position with the link fuse thereon ready to be installed in position by the stick;

Figure 2 is a vertical section taken on line 2—2 in Figure 1, and largely forming another elevation of the fuse link stick as seen from the right in said Figure 1;

Figure 3 is a vertical section taken on line 3—3 in Figure 2;

Figure 4 is a transverse section taken on line 4—4 in Figure 1;

Figure 5 is a side elevation similar to that of Figure 1, partly in section to disclose constructional detail.

2

Throughout the views, the same reference numerals indicate the same or like parts.

When linemen and wire operators are installing or repairing cables on high structures, and particularly on poles, one of their duties is to install or replace fuse links which are of special construction and usually located in elevated positions. It is, of course, dangerous to attempt making contact with the fuses by the hands, and instead some elongated means, such as special poles or sticks, have been used for directly engaging the fuses and elevating the same into position, and thereby installing the latter in order to avoid accidents involving burns and possible fatalities. Certain makeshift means have, of course, been resorted to heretofore, and it has sometimes occurred that the fuses carried upon said means have been accidentally displaced and dropped therefrom before reaching the connection upon which they were intended to be mounted. As the fuse involved has thus dropped to the ground, it has either been lost or damaged so that a new fuse has been placed upon the device used, and been raised into position and ultimately installed as originally intended for the fuse that was lost by accident. Such loss is only one feature of the misadventure, for in each case the lineman must climb down the ladder or pole upon which the installation is being made, and then climb up again before he can resume operations, which means a loss of time in addition to loss of the fuse and longer outage to the customer.

Upon considering this problem, it has occurred to me that a special fuse link stick should be available which would automatically prevent loss of the fuse while being raised into position and installed and which also would automatically release the fuse when once installed without further manipulation. As a result, I have succeeded in producing a fuse stick as generally outlined which will now be more fully described.

Hence, in the practice of my invention, and referring again to the drawing, a fuse link stick, generally indicated at 1, primarily includes an elongated cylindrical handle 8 of wood treated to be moisture proof and highly dielectric or of rigid plastic material of insulating character having upon a shoulder 9 thereof a reduced extension 10 upon which is mounted a tube 11 fixed to the extension 10 by means of a pin or screw 12. The upper end of tube 11 is preferably threaded, as indicated at 13 in Figure 3, with an internally-threaded cap 14 screwed thereon, or it may be welded or brazed in position. Immediately below

cap 14 is a pivot pin 15 extending transversely through tube 11 upon which is mounted the upper opposite portions 16, 16 of a pendent arcuate member 17.

From the upper arcuate intermediate portion 18, but spaced below pivot pin 15, extends a tubular latch arm 19 and terminates upon its outer end in a flange 20. Upon the inner threaded end of tubular arm 19 at 21 is screwed a stop nut 22 preferably brazed or welded to the intermediate arcuate portion 18 of channel member 17, and upon the inner surface of the mentioned portion 18 is located a second nut 23 screwed upon the inner extremity of tubular arm 19 so that the latter is held in a fixed projecting position upon channel member 17. From an intermediate portion of the top of hollow arm 19 to the outer flange 20 extends an upwardly-open slot 24 through which extends an upwardly-projecting lug 25 of a latch plunger 26 slidably mounted in tubular arm 19 in such fashion that the plunger is slideable within the limits permitted by slot 24 to the upwardly-extending lug 25. The slot 24 does not actually reach the flange 20, but terminates a very short distance therefrom, at 27, so that the upper smaller loop portion 28 of a link 29 may be seated thereon and located between lug 25 and flange 20 and rest on the tube portion 27 when plunger 26 is disposed in its outermost position. From the upper portion of lug 25 extends an outwardly-projecting latch pin 30 in effective position to confine the upper portion 28 of fuse link loop 29 between lug 25 and flange 20 on arm 19, the pin being preferably screwed into the lug in order to fix it permanently in position thereon.

In order to control the position of plunger 26 and its lug 25 with respect to the arm 19, the plunger has the outer end of a rod 31 screwed into the threaded bore 32 thereof. The opposite end of rod 31 projects inwardly within channel member 17 through a vertical slot 33 in handle tube 11 and within the latter extends into an attached pivot member 34 retained upon rod 31 by a set screw 6 and mounted upon the intermediate portion of a second pivot pin 35 extending transversely through the mentioned handle tube 11 a short distance below the first-mentioned pivot pin 15 and in parallelism therewith.

The arrangement is such that when a fuse assembly including a fuse casing 36 containing a fuse, not shown, terminating in reduced ends 37 (one shown) with copper strand wires 38 connected to the fuse link connection 39 from which the fuse link portion or loop 28 extends, the latter may be connected to a switch binding post upon an elevated structure or pole by means of the fuse stick 7 thus far described. The tubular arm is adapted to suspend loop 29 thereon when the opposite end loop (not shown) or some other portion of the fuse link is connected to a portion on handle 8 spaced a distance below arm 19, not shown as being part of the invention. Thus, if channel member 17 is manually raised into the position indicated in broken lines at 40 in Figure 1, it will be evident that plunger 26 will be withdrawn toward its innermost limit by rod 31 and its pivot member 34 mounted on pivot pin 35, because pivot pin 35 is located a distance below pivot pin 15 of the channel member and does not coincide therewith. The result is that latch pin 30 is withdrawn to the position indicated at 41 in broken lines, leaving a considerable gap between the same and flange 20, which readily allows the upper smaller arcuate end 28 of fuse link 29 to be inserted therebetween. When the

fuse link loop 29 is thus pendently located between lug 25 and flange 20, channel member 17 is allowed to drop its normal pendent vertical position, as shown in full lines in Figure 1, when rod 31 will push plunger 26 and its lug 25 toward flange 20, closing the gap between latch pin 30 and the flange and thus imprisoning the upper small loop portion 28 of fuse link loop 22 beneath the mentioned pin. If then the handle 8 is grasped and the entire stick 7 raised with fuse link loop 29 depending with the fuse assembly including wires 38 and fuse tube 36 with its reduced end 37 depending from the arm 19 on the stick, the fuse link loop 29 may be brought up into proper position upon the switch or other connection to which it is intended to be connected. When the link loop 29 has been properly installed, lowering of the handle 8 with consequent lowering of the upper tubular portion 11 thereof will cause latch pin 30 to act for the moment as though pivoted upon the upper small loop portion 28 of link loop 29, rocking channel member 17 into the position indicated in broken lines at 40 already referred to. The immediate result is that latch pin 30 is brought into the spaced position indicated in broken lines at 41, allowing the arm 19 and its appurtenances to drop away from fuse link loop 29, which automatically leaves the fuse link in place as installed and releases the fuse link stick 8 and allows channel member 17 with its arm 19 to drop back into the full line position wholly out of contact with the fuse link.

As already intimated, it is self-evident that the fuse link is provided at its lower end with a loop portion corresponding to the upper loop portion 29, and that the main handle or staff 8 of the fuse stick may be provided at an intermediate point with a more or less conventional side arm or projection (not shown) for engaging another portion or the lower loop portion of the fuse link when the upper loop portion 29 is engaged upon arm 19. Such conventional arms or projections, for example, are shown in the patents of C. A. Fox, No. 2,102,894, dated December 21, 1937, and of D. C. Hubbard, No. 2,438,121, dated March 23, 1948, but any other form of flexing, pivoted or resiliently-urged sliding arm suitable for the purpose may obviously be used, the invention not being directed thereto but to the upper structure described above.

Manifestly, variations may be resorted to and parts and features may be modified or used without others within the scope of the appended claims.

Having now fully described my invention, I claim:

1. A fuse link stick of the type adapted to engage with an upper end loop upon a fuse link and with another portion of the latter spaced a distance below the upper end loop, said fuse link stick including an elongated handle, a pendent member pivotally connected at the upper end thereof to the upper end of the handle, a link-supporting arm projecting outwardly from the pendent member a predetermined distance below the upper pivoted portion of the latter substantially at right angles thereto for engaging with said upper end loop of said fuse link, a stop upon the outer end of the arm, a latch member slidably mounted on the latter with an outwardly-projecting latch portion directed toward the stop and adapted to approach and recede from said stop according to the movement of the latch member on said arm, and a rod connected at one end to said latch member and at the other end

pivotedly connected to said handle a predetermined distance below the pivotal mounting of said pendent member.

2. A fuse link stick of the type adapted to engage with an upper end loop upon a fuse link and with another portion of the latter spaced a distance below the upper end loop, said fuse link stick including an elongated handle, a pivot pin extending transversely through the upper end of the handle, a channel member pivoted at the upper ends of the sides thereof to the ends of the pivot pin allowing the channel member to swing pendently about a transverse axis, a tubular arm adapted to support the upper end loop portion of the fuse link fixed on the upper intermediate portion of the channel member a predetermined distance below and intermediate the pivoted portions thereof and extending prependicularily outwardly from the tubular arm, the latter terminating at the outer end in a flange and having an elongated and upwardly-open slot within the flange, a latch member slidably mounted in said tubular arm, a lug extending upwardly through the elongated slot from the latch member, a latch portion projecting rigidly outwardly from the upper portion of said lug toward the flange and spaced above said tubular arm a sufficient distance above the arm to receive said upper end loop portion of the fuse link therebetween, a second pivot pin upon said handle disposed a predetermined distance below the first-mentioned pivot pin, and a rod rigidly connected at one end to said latch member and having a portion at the other end thereof pivotally mounted upon said second pivot pin.

3. A fuse link stick of the type adapted to engage with an upper end loop upon a fuse link and with another portion of the latter spaced a

distance below the upper end loop, said fuse link stick including an elongated handle, a hollow portion upon the upper end of the handle, a pivot pin extending transversely through the upper hollow end of the handle, a channel member pivoted at the upper ends of the sides thereof to the ends of the pivot pin allowing the channel member to swing pendently about a transverse axis, a tubular arm adapted to support the upper end loop portion on the fuse link fixed on the upper intermediate portion of the channel member a predetermined distance below and intermediate the pivoted portions thereof and extending perpendicularly outwardly from the tubular arm, the latter terminating at the outer end in a flange and having an elongated and upwardly-open slot within the flange, a latch member slidably mounted in said tubular arm, a lug extending upwardly through the elongated slot from the latch member, a latch pin projecting rigidly outwardly from the upper portion of said lug toward the flange and spaced above said tubular arm a sufficient distance to receive said upper end loop portion of the fuse link between the arm and the latch pin, a second pivot pin within the hollow portion of the handle and disposed a predetermined distance below and parallel to the first-mentioned pivot pin, and a rod rigidly connected at one end to said latch member with a pivot portion upon the other end of said rod pivotally mounted upon the second pivot pin within the hollow portion of said handle, the latter having a slot in said hollow portion thereof through which said rod extends.
